UNITED STATES PATENT OFFICE.

GEORGE ROBINSON AND GEORGE CUTSFORTH, OF RIDDLE, OREGON.

MOWING-MACHINE.

No. 838,904.

Specification of Letters Patent.

Patented Dec. 18, 1906.

Application filed May 26, 1906. Serial No. 318,844.

To all whom it may concern:

Be it known that we, GEORGE ROBINSON and GEORGE CUTSFORTH, citizens of the United States, and residents of Riddle, in the county of Douglas and State of Oregon, have invented certain new and useful Improvements in Mowing-Machines, of which the following is a specification.

This invention is an improvement in mowing-machines, and relates particularly to a track-clearing attachment whereby heavy vines and grasses may be cut at the outer end of the sickle-bar to avoid clogging of the bar and to aid the divider in separating the cut from the uncut grass; and the invention consists in certain novel constructions and combinations of parts, as will be hereinafter described and claimed.

In the drawings, Figure 1 is a perspective view of our invention as in use. Fig. 2 is a rear elevation of the outer end of the cutter-bar provided with our improved apparatus, parts being broken away. Fig. 3 is a sectional side elevation of the upright cutter, and Fig. 4 is a detail view of one of the upright or vertical sickles.

In carrying out the invention it will be noticed that the improvements are applied to a finger-bar A, receiving a sickle B, and these parts may be constructed and arranged to operate in the usual manner, suitable means being provided for operating the sickle B, and the latter having at its inner end a lug B' or other suitable means for the connection of a pitman C for operating the vertical sickles, in the manner presently described, as the sickle B is reciprocated by the usual operating means.

At the outer end of the finger-bar a divider D is provided, and upon the outer end of the finger-bar is mounted the frame E for the vertical sickles. This frame C is provided at its lower end with a foot E', which may be bolted upon the finger-bar, and the upright frame E, being thus securely held in place, has its back plate E', provided with the forwardly-projecting lugs or bars E², whose front ends E³ are turned inwardly to lap along the front sides of the sickle-bars F, to which the blades F' of the vertical sickles are secured. By this means the vertical sickles are held to the upright frame-bar, so they may be reciprocated and still bear at their rear edges against the plate E', so they may be guided accurately in their vertical movements. At their upper ends the ver-

tical sickle-bars are turned to form eyes F², in which are fitted the forwardly-projecting studs G' on the links G, which connect the vertical sickles with the lateral arms H' of the rocker H, which is pivoted at the juncture of the arms H' with the depending arm H², the latter being connected by the pitman C with the reciprocating horizontal sickle-bar, as before described. By the described construction it will be noticed the vertical cutter may have its sickles operate reciprocally to cut the thick heavy vines at the outer end of the cutting apparatus. It will be noticed that the entire front edges of the blades F' of the vertical sickles are sharpened, and the sickles are so arranged and operated as to avoid the overlapping or overriding of the blades, they being operated by the rockers only to the extent of two-thirds of the distance across each blade. By reason of this it will be seen that at no time does the edge of one blade pass the edge of the other blade, so that we are able to prevent the overlapping of the blades and to provide for cutting in each operation of the sickle. Further, by making the blades with all sharp edges, as shown, they can be ground on an ordinary grindstone or sickle-grinder.

The pitman C, which extends above the horizontal sickle and extends on a straight line to the head on the lug B', is provided on its upper side with a series of teeth C', whose sides C² facing inwardly or toward the main frame of the machine are approximately square, and whose opposite sides C³ are inclined so that as the pitman moves inwardly it will draw the cut swath toward the main frame or carriage of the machine and then on the outward movement of the pitman will slip below the swath, thus keeping the cut grass, vines, &c., away from the track-clearer and aiding the latter in separating the cut from the uncut material.

The frame E for the upright sickle being provided with the foot-piece E' facilitates the application of the improvement to mowers of the ordinary construction.

The vines and grasses grow to considerable heights in some localities, and we find it better to bring the vines down to the vertical sickles than to extend said sickles up beyond a reasonable height. To this end we provide a depressing-arm I, which is secured at I' to the upper end of the frame E and inclines forwardly toward its upper end, extending to a sufficient height to override the

- tall vines, &c. This arm I preferably has the parallel side bars I^2 , and between these bars I^2 we provide a series of antifriction-rollers L^3 , which are disposed vertically edgewise 5 and are journaled in the depressing-arm and are arranged each to overlap the adjacent rollers and to project at their free edges below the lower or forward edge of the upwardly-inclined arm I, thus producing an 10 antifriction-surface which extends from the upper end of the depressing-arm practically to the vertical cutters and facilitates the depression of the heavy vines, &c., and avoids any dragging action of said vines 15 along the lower edge of the arm, thus preventing compacting of the vines into a mass and dragging such vines and grass downwardly to the vertical cutters and enabling the use of a short auxiliary vertical cutter. 20 A short cutter is desirable for several reasons. In the first place, it reduces weight and provides for a satisfactory operation by preventing the wabbling and vibrating of the cutter, &c., which would result from its 25 extreme height. The depressing-arm with the antifriction-rollers is also desirable in that it has a tendency to ride up on the vines or other heavy growth, and so operates with a lifting action at the outer end of the cutter- 30 bar.
- We claim—
1. A mowing-machine having a horizontal sickle and a cutter at its outer end and composed of vertical sickle-bars, a frame in which 35 said sickle-bars may be reciprocated, the bars being provided at their upper ends with eyes, a rocker having lateral arms and links connecting the same with the eyes of the vertical cutters, said rocker having also a depending 40 arm and being pivotally supported at the juncture of its lateral and depending arms, a pitman connected with said depending arms and provided on its upper side with teeth inclined on their outer sides and approximately 45 upright and square on their inner sides whereby they may operate upon the cut grass, &c., and connections between said pitman and the horizontal sickle-bar, substantially as set forth.
  2. A mowing-machine having a main 50 sickle, a supplemental vertical cutter at the outer end of the main sickle, and a depressing-arm inclining upwardly and forwardly from the supplemental sickle and provided with a series of antifriction-rollers projecting 55 beyond its lower or front edge, substantially as set forth.
  3. The combination with the vertical sickle-bars and their blades, of the vertical frame for said bars having a back plate and forwardly-projecting lugs having their front ends inturned to overlap the front edges of the vertical sickle-bars, the depressor-arm having its side barslapping along the opposite sides of the upper ends of the vertical 60 sickles and secured to the frame therefor, and means for reciprocating the vertical sickles, substantially as set forth.
  4. A mowing-machine having a horizontal sickle, a vertical cutter at the outer end 70 thereof, a pitman for operating the vertical cutter, and extending above the horizontal sickle, and provided with teeth inclined on their outer sides and square on their inner sides whereby to operate upon the cut material, and connections whereby the said pitman may be operated, substantially as set forth.
  5. A vertical supplemental cutter for mowing-machines having an upwardly and 75 forwardly projecting depressor-arm provided with projecting antifriction-rollers, substantially as set forth.

GEORGE ROBINSON.
GEORGE CUTSFORTH.
